UNITED STATES PATENT OFFICE.

WILLIAM HENRY FYAN, OF PORT HURON, MICHIGAN.

DESIGN FOR A VEHICLE-THILL.

SPECIFICATION forming part of Design No. 33,516, dated November 6, 1900.

Application filed July 3, 1899. Serial No. 722,651. Term of patent 14 years.

To all whom it may concern:

Be it known that I, WILLIAM HENRY FYAN, a citizen of the United States, residing at Port Huron, county of St. Clair, State of Michigan, have invented and produced a new and original Design for Vehicle-Thills, of which the following is a specification, reference being had to the accompanying drawing, forming part thereof.

10 My invention is a design for vehicle shafts or thills; and it consists of two pair of thills engaged together of the novel shape and contour illustrated in the accompanying drawing, which is a perspective view of the design.

15 As shown in the drawing, the two inside thills are straight and substantially at right angles to the bars *a*, while the two outside thills are in the form of a compound curve.

The distinguishing feature of my design is a double pair of shafts having the inside 20 thills of each pair of shafts straight and parallel to each other and extending outwardly at right angles from the bar *a*, while the outside thills of each pair of shafts are in the form of a compound curve. 25

I claim—

The design for vehicle-thills herein shown and described.

In testimony whereof I sign this specification in the presence of two witnesses.

WILLIAM HENRY FYAN.

Witnesses:

HENRY C. HOPE,
ALFRED M. HUME.
